UNITED STATES PATENT OFFICE.

CARL OSCAR SCHNEIDER, OF CHICAGO, ILLINOIS, ASSIGNOR TO R. FRIEDLANDER & CO., A CORPORATION OF ILLINOIS.

CURRENT-INTERRUPTER.

SPECIFICATION forming part of Letters Patent No. 716,584, dated December 23, 1902.

Application filed June 14, 1902. Serial No. 111,628. (No model.)

To all whom it may concern:

Be it known that I, CARL OSCAR SCHNEIDER, a citizen of the United States of America, and a resident of Chicago, in the county of Cook 5 and State of Illinois, have invented certain new and useful Improvements in Current-Interrupters, of which the following is a specification.

The present invention relates to that type 10 of frequency-interrupters generally known as the "electrolytic" interrupter, and has for its object to provide a simple, durable, and effective device or apparatus in which a uniform area of exposure of the anode-surface 15 is maintained during continued operation and with which the degree or extent of such anode exposure can be varied at the will of the operator in a ready and convenient manner, all as will hereinafter more fully appear, 20 and be more particularly pointed out in the claims.

In the accompanying drawings, illustrative 25 of the present invention, Figure 1 is a central sectional elevation of a frequency-interrupter embodying the present invention; Fig. 2, a fragmentary sectional elevation illustrating a modification.

Similar numerals of reference indicate like 30 parts in both views.

Referring to the drawings, 1 represents a cell or containing vessel of any usual and suitable form and material and adapted to contain the fluid electrolytic conductor, such as a dilute solution of sulfuric acid; 2, a 35 removable cover for the cell or vessel 1 and which is preferably employed to support the respective anode and cathode of the interrupter.

3 is the cathode, of any usual form, preferably a lead plate or other conductor of large 40 surface as compared with the anode. Such cathode is suspended from the cover 2 and is provided with a binding-post 4 or other usual attachment, by means of which connection 45 is had with one pole of the battery or other source of electrical supply.

5 is the anode, formed by a conducting rod or wire of any metal adapted to resist chemical action on the part of the liquid electrolytic conductor employed in the apparatus. 50

6 is a tube of insulating material surround-

ing the anode 5 and preferably formed with a bore of much greater diameter than that of the anode 5, and in which case its respective ends or extremities are reduced to constitute 55 guides for the said anode, as shown. In the present invention the anode 5 is adapted to have free longitudinal movement in the insulating tube or housing 6, for the purpose hereinafter set forth.

60 7 is an abutment or rest arranged a short distance away from the lower end of the insulating tube or inclosure 6 and adapted to limit the degree of downward movement of the wire or rod anode 5 and the consequent 65 extent of surface exposure of such anode. The described arrangement constitutes a material part of the present invention in that it compensates in a very effective and automatic manner for the gradual erosion of the 70 cathode during extended use by the acid electrolyte, and consequently avoids the corresponding decrease in the extent of surface exposure of such cathode, with the corresponding decrease in current intensity usual 75 to the ordinary type of electrolytic interrupter heretofore in general use.

The abutment or rest 7 may be formed integrally or otherwise on the bottom of the containing vessel or cell 1, as illustrated in 80 Fig. 1, or may be in the form of a member 7', entirely distinct from such bottom, as illustrated in Fig. 2.

In the present invention the extent of surface exposure of the cathode and the consequent change in the intensity of the current is effected by an adjustment of the distance 85 between the lower end of the insulating tube or inclosure 6 and the abutment or rest 7, either by the adjustment of one or the other 90 of said parts.

In Fig. 1 a construction is shown in which the insulating-tube 6 is made vertically adjustable, and for this purpose is provided with a screw-threaded sleeve 8, having an operating head or handle 9 at its upper end and adapted to screw in the screw-threaded bore of the bushing 10, that is secured to the cover 2 of the main containing vessel, to effect the desired adjustment of the said insulating-tube 6.

100 In Fig. 2 a construction is shown wherein

the rest or abutment 7' is made vertically adjustable, and to this end is connected to a vertically-extending stem 11, the upper end of which is screw-threaded and is engaged by an operating - nut 12, that has bearing in the cover portion 2 of the containing vessel.

13 is a lateral neck near the upper end of the insulating-tube 7, the purpose of which is to prevent any undue rising of the liquid electrolyte within said tube from any usual cause, and thus avoid any leakage of such electrolyte over the top of the apparatus and the consequent inconvenience resulting therefrom.

15 The anode 5 is provided with a binding-post 14 or other usual attachment, by means of which connection is had with a pole of the battery or other source of electrical supply.

Having thus fully described my said invention, what I claim as new, and desire to secure by Letters Patent, is—

1. In a current-interrupter of the character described, the combination with a cell, a contained liquid electrolyte and a cathode element, of an anode element, an insulating tubular inclosure in which said anode is free to move, and an alined abutment or rest arranged in separated relation to the end of the tubular inclosure, substantially as set forth.

30 2. In a current-interrupter of the character described, the combination with a cell, a contained liquid electrolyte and a cathode element, of an anode element, an insulating tubular inclosure in which said anode is free to move, an alined abutment or rest arranged in separated relation to the end of the tubular inclosure, and means for effecting an adjustment between the said abutment or rest

and the end of the tubular inclosure, substantially as set forth. 40

3. In a current-interrupter of the character described, the combination with a cell, a contained liquid electrolyte and a cathode element, of an anode element, an insulating tubular inclosure in which said anode is free to move, an alined abutment or rest arranged in separated relation to the end of the tubular inclosure, and means for effecting an adjustment between the said abutment or rest and the end of the tubular inclosure, the 45 same comprising a screw-threaded sleeve upon said tubular inclosure and a bushing secured to the cover of the cell, and provided with a screw-threaded bore for engagement with such screw-threaded sleeve, substantially as 50 set forth.

4. In a current-interrupter of the character described, the combination with a cell, a contained liquid electrolyte and a cathode element, of an anode element, an insulating tu- 60 bular inclosure in which said anode is free to move, an alined abutment or rest arranged in separated relation to the end of the tubular inclosure, and a lateral neck formed near the upper end of such tubular inclosure and 65 forming a communication between such portion of the tubular inclosure and the upper portion of the main cell, substantially as set forth.

Signed at Chicago, Illinois, this 10th day of 70 June, 1902.

CARL OSCAR SCHNEIDER.
